UNITED STATES PATENT OFFICE.

WILLIAM LINDSAY SIMPSON, OF SAN FRANCISCO, CALIFORNIA, ASSIGNOR TO
BETHLEHEM SHIPBUILDING CORPORATION, LTD., OF BETHLEHEM, PENN-
SYLVANIA, A CORPORATION OF DELAWARE.

DOUBLE-RIVETING MACHINE.

1,351,444.

Specification of Letters Patent. Patented Aug. 31, 1920.

Application filed December 31, 1918. Serial No. 269,084.

To all whom it may concern:

Be it known that I, WILLIAM LINDSAY SIMPSON, a citizen of the United States, and residing in the city and county of San Francisco, State of California, have invented a new and useful Double-Riveting Machine, of which the following is a specification.

In the operation of riveting with such pneumatic devices as the Boyer riveter or Boyer "gun," it is in many instances the practice for the operator to apply the riveter to the work or manually to manipulate the pneumatic tool by himself directly applying it to the work to be riveted.

In various operations in boiler shops, shipyards and the like, there is a great deal of work, such as straight riveting, particularly in the production of fabricated parts of ships and the like, which can be more readily and expeditiously effected by transporting the plates or other elements to be riveted, after they have been bolted up, directly to the riveting apparatus, by any suitable means, as by a crane or kindred apparatus.

In my present invention, the work is brought to the riveter and the latter and its adjuncts suitably supported, adjusted or advanced to the work by the flow of motive fluid regulated by the workman's foot, with the result that the vibration, shock and jar- ring incident to the riveting operations which, as is well known, are fatiguing to the operator, are practically all removed from the operator and absorbed in the rig- ging or supporting and actuating mecha- nism which my invention embraces.

To the above ends, my invention comprehends a novel construction of supporting standards or uprights, one of which fixedly supports a pneumatic riveter or kindred tool, while the other supports a second riveter or tool in alinement with the first, but equipped with novel means whereby the operator can without fatigue, first, readily advance the second riveter to the work, and thereafter put both riveters into synchronous but opposite operation until the riveting operation is completed, which requires but a few seconds, after which the second riveter is automatically caused to recede from the work, so that another heated rivet can be inserted in the work and subjected to the riveting operation.

With the foregoing objects in view, my invention comprehends a double riveting machine of the general character represented in the accompanying drawings and herein- after described and claimed, and which em- braces,—means for maintaining in relatively fixed position a pneumatic riveter,—means for maintaining in longitudinal adjustabil- ity so that it can be advanced and retracted, and in alinement with the fixed riveter, a second pneumatic riveter,—means under the control of the foot of the operator by which the desired advance and retraction of the second tool may be effected,—and means also under the control of the foot of the operator by which the two riveters can be caused simultaneously to operate to effect the riveting operation, when the article to be riveted is subjected to the operation of the alined riveters,—the entire operation being, as explained, one which leaves the hands of the operator free and reduces the fatigue of the operator to a minimum.

To the foregoing ends my invention em- braces supporting mechanism for the oppo- sitely disposed pneumatic tools,—means by which the tools can be applied to, retained in position in and removed from the sup- ports,—a seat for the operator,—a pedal mechanism under the control of the feet of the operator,—a source of motive fluid supply,—valve mechanism under the control of the pedal mechanism connected with the source of fluid supply, by means of which, first, the adjustable tool may be advanced and retracted relatively to its support, by a fluid-controlled advancing and retracting device, and, second, both tools be caused to operate upon the rivet simultaneously and oppositely,—all as hereinafter set forth.

For the purpose of illustrating my inven- tion, I have shown in the accompanying drawings one form thereof which is at pres- ent preferred by me, since the same will be found in practice to give satisfactory and reliable results, although it is to be under- stood that the various instrumentalities of which my invention consists can be variously arranged and organized and that my in- vention is not limited to the precise arrange- ment and organization of these instrumen- talities as herein shown and described.

Figure 1 represents a side elevation of a riveting machine embodying my invention.

Fig. 2 represents an end elevation of the machine of Fig. 1, viewed from the right hand side of said Fig. 1.

Fig. 3 represents a top plan view of the machine of Figs. 1 and 2.

Fig. 4 represents a side elevation (partly in section) on the dotted line 4—4 of Fig. 3.

It is to be understood that wherever reference is made to these pneumatic hammers or tools, that such reference is to be interpreted as meaning any conventional type of pneumatic riveter, which embodies a hammering piston with or without a distribution valve to control the reciprocations of the hammering piston which impacts upon the shanks of the rivets.

Referring now to the drawings:—1 designates a foundation or base plate of any preferred character, upon which are erected a plurality of vertically disposed aligned standards, uprights or steel plates, respectively designated 2 and 3, the inner edges of which are separated a certain distance to form a gap 6, within which the articles to be riveted such as the plates or the like 40 are successively introduced and manually adjusted so that the rivets 41 are one by one brought into registry with the opposing rivet sets 11^x and 15^x, hereinafter referred to.

30 The standards 2 and 3 are preferably laterally braced or stayed by opposite counterpart brace plates, 4, 4^x of the standard 2, and 5, 5^x of the standard 3,—bolted angle irons of the usual character being used to effect the connection of both standards with the base plate and also with the brace plates.

7 designates a laterally extending frame projecting from the standard 3, to which it is bolted or otherwise attached, to the outer 40 end of which is applied a seat 8 for the operator, whose feet are adapted to rest upon the foot plates 9, 9^x which project laterally from both sides of the standard 3 and the outer sides of the brace plates 5, 5^x, below the seat.

Above these foot plates are located the pedals 30 and 32 which control the valve mechanism for the motive fluid supply, and are hereinafter referred to.

50 Upon the tops of the standards 2 and 3 are supported the two oppositely operating pneumatic riveters which I employ, 11 designating the left hand or fixed riveter and 15 the opposite or right hand coacting longitudinally adjustable riveter, it being apparent that in the assemblage of said riveters, one of them is relatively stationary with relation to its support and the other capable of relative adjustment toward and away from the other, whereby plates or articles of different thicknesses can be readily riveted.

Referring first to the left hand riveter 11, the latter may be a typical pneumatic hammer of the "Boyer" type, which has a handle 14 to which the supply pipe 27 is

coupled, and which is supported within a casing 13 mounted on a tool-bed-plate 10 superposed upon and connected with the standard 2, and which has a vertical abutment 12 against which the handle end of 70 the riveter abuts when said fixed or stationary riveter is in position.

11^x is the rivet set of the fixed riveter 11 which alines with the rivet set 15^x of the adjustable riveter 15 when both riveters 75 are assembled.

Referring now to the right hand or adjustable riveter 15, the latter may be a typical Boyer or other pneumatic riveter similar to said fixed riveter, but having its 80 handle removed and its cylinder is screwed into a head 22, which is itself attached to or integral with the outer end of a plunger 20, the piston head 21 of which operates within a fixed air cylinder 19, preferably 85 supported on a bracket 18 extending outwardly from the outer edge of the standard 3 to which it is bolted or otherwise secured.

A motive fluid supply pipe 28 which corresponds generally to the supply pipe 27 90 of the handle of the fixed tool conveys the motive fluid into the tool head 22, so that when the two riveters are in operation or in operative proximity, the motive fluid supply into both of them will through a suitable distribution valve,—occasion the reciprocations of the hammering pistons upon the rivet sets of the respective riveters.

The forward end of the adjustable riveter 15 is contained within a casing 17 mounted on the bed plate 16 superposed upon and connected with the standard 3, and in the positioning of said riveter, it is obvious that its cylinder can be readily 105 screwed into the tool head 22.

The tool head 22 being, as explained, carried by the plunger 20, the piston head 21 of which is within the stationary cylinder 19, which devices serve as a pneumatic 110 holder-on, it will be apparent that the movement of said tool head and its riveter 15 toward or from the fixed riveter 11 to occasion the desired separation of the two rivet sets prior to the riveting operation, is 115 under the control of the operator through his control of the motive fluid conveyed to either end of the cylinder 19 through the pressure supply pipes 25 and 26, as best shown in Fig. 4, said cylinder being provided with the stuffing box 23.

The operation is as follows:—

Referring now to the control by the operator of the fluid supply, which first through the pneumatic holder-on, comprising the fixed cylinder 19, piston 21 and piston rod or plunger 20 enables him to position the movable riveter 15 relatively to the fixed riveter 11 and then after such positioning enables him to effect the riveting opera- 130

tions, it will be apparent that the air supply pipes 25 and 26 of the cylinder 19 extend down as best seen in Figs. 1 and 2 to a left hand air valve 31 the lever 36 of which is connected with a pedal rod 35 extending up through the foot plate 9 to the left-hand pedal 30 which after depression by the operator's left foot is elevated to normal position by a spring or other tension device 34 interposed between it and the foot plate 9,—so that by the proper depression of said pedal the operator can admit air to the cylinder 19 at either end,—first of course to the outer end to advance the adjustable riveter 15 into the desired position and afterward to the inner end of said cylinder to retract the tool back again to normal after the riveting operation has been completed.

After the foregoing operation and the desired positioning of the movable riveter has been effected, the control of the reciprocation of the hammering pistons of both riveters is effected by the supply of motive fluid through the supply pipes 27 and 28, which extend from the respective riveters downwardly (see Fig. 2) to a right hand air valve 33, the lever 39 of which is connected with the pedal rod 38 extending up through the foot plate 9^x to the right-hand pedal 32, which after depression by the operator's right foot is elevated to normal position by a spring or other tension device 37 interposed between it and the foot plate 9^x,—so that by the proper actuation of said right-hand pedal, the operator can control the inlet and exhaust to the distribution valves of the two riveters.

The positions of the fixed and removable riveters 11 and 15 can be reversed without departing from the spirit of my invention.

It will be apparent from the foregoing that the operator with one foot as his left foot can readily control the action of the pneumatic holder-on, seen at the right of Figs. 1, 3, and 4, and with his other foot as the right can control the starting and stopping of the reciprocations of the hammering pistons of the fixed and adjustable riveters 11 and 15, all without fatigue, and in addition the operator is not subjected to the jar and vibration incident to the operation of the riveters. By the conjoint operation of the two alined riveters the rivets will be expeditiously and effectively driven, since the pneumatic holder-on coacts in a very effective manner during the riveting operation as will be evident to those skilled in the art.

I have deemed it unnecessary to show in detail the construction of the foot operated valves 31 and 33, since it will be apparent that any suitable cock or valve which will control or cut off the inlet of the motive fluid in the manner described will be effective for this purpose. While I preferably

employ the well known Boyer riveter, it will be evident that any other conventional type of pneumatic riveter may be employed without departing from the spirit of my invention.

70

It will now be apparent that I have devised a novel and useful construction of a double riveting machine which embodies the features of advantage enumerated as desirable in the statement of the invention and the above description, and while I have, in the present instance, shown and described a preferred embodiment thereof which will be found in practice to give satisfactory and reliable results, it is to be understood that the same is susceptible of modification in various particulars without departing from the spirit or scope of the invention or sacrificing any of its advantages.

75

Having thus described my invention, what I claim as new and desire to secure by Letters Patent, is:—

80

1. The combination of a fixed horizontal pneumatic riveter, an adjustable horizontal pneumatic riveter in longitudinal alinement therewith, fluid pressure means for actuating said latter riveter in either direction, a seat supported in proximity to and below said latter riveter, and a foot valve below said seat for controlling said fluid pressure means.

90

2. In a device of the character stated, a fixed horizontal pneumatic riveter, a longitudinally movable horizontal pneumatic riveter in horizontal alinement therewith, means for actuating said latter riveter in either direction, and foot controlled means for simultaneously starting and stopping said riveters.

100

3. In a device of the character stated, a fixed horizontal pneumatic riveter, a longitudinally movable horizontal pneumatic riveter in horizontal alinement therewith, foot-actuated fluid pressure means for actuating said latter riveter in either direction, and another foot-actuated fluid pressure means for effecting the starting and stopping of both of said riveters, said foot-actuated means being located on opposite sides of said riveters.

110

4. In a device of the character stated, a fixed pneumatic riveter, a longitudinally movable pneumatic riveter in alinement therewith, a seat for the operator, foot-actuated fluid pressure means for actuating said movable riveter in either direction, and foot-actuated means for effecting the simultaneous starting and stopping of both of said riveters, said foot actuated means being located on either side of said seat.

120

5. A riveting machine in which are combined the following elements:—a supporting frame-work which comprises two separated vertical standards, a horizontal pneumatic tool fixed upon one of said standards, a

130

- horizontal pneumatic tool movable upon the other of said standards operatively alined with the first tool, and foot-actuated means under the control of the operator for simultaneously operating both tools, in combination with foot actuated means for actuating said movable tool in either direction.
6. A riveting machine in which are combined the following elements:—a supporting framework which comprises two separated vertical standards, a horizontal pneumatic tool fixed upon one of said standards, a horizontal pneumatic tool adjustable upon the other of said standards toward and from said first tool and operatively alined therewith, foot-actuated means under the control of the operator for longitudinally positioning the adjustable tool, and a second foot actuated means similarly under the control of the operator for simultaneously operating both tools.
7. A riveting machine in which are combined the following elements:—a supporting framework which comprises two separated vertical standards, a horizontal pneumatic tool fixed upon one of said standards, a horizontal pneumatic tool upon the other of said standards horizontally alined with the first tool, a seat for the operator below said latter tool, and a foot actuated motive fluid supply below said seat and under the control of the foot of the operator for simultaneously operating both tools.
8. A riveting machine in which are combined the following elements:—a supporting framework which comprises two separated standards, a horizontal pneumatic tool fixed upon one of said standards, a horizontal pneumatic tool adjustable upon the other of said standards toward and from said first tool and horizontally alined therewith, a seat for the operator below said adjustable tool, a foot actuated motive fluid supply below said seat and under the control of the operator for longitudinally positioning the adjustable tool, and another foot actuated motive fluid supply similarly under the control of the operator for simultaneously operating both tools.
9. A riveting machine in which are combined the following elements:—a supporting framework which comprises two separated vertical standards, a tool bed plate mounted upon one of said standards, a casing on said plate for retaining in fixed horizontal position a pneumatic tool, means mounted upon the other of said standards for retaining in adjustable position and in horizontal alinement with the first tool, an adjustable pneumatic tool, guiding means on its standard for the movable portion of said adjustable tool, and foot actuated means under the control of the operator for simultaneously operating both tools.
10. A riveting machine in which are combined the following elements:—a supporting framework which comprises two separated upright standards, a tool bed plate mounted upon one of said standards for retaining in fixed horizontal position a pneumatic tool, means mounted upon the other of said standards for retaining in adjustable position and in horizontal alinement with the first tool, an adjustable pneumatic tool, means on said frame work for guiding the forward portion of said adjustable tool, means under the control of the operator for longitudinally positioning the adjustable tool, and separate means similarly under the control of the operator for simultaneously operating both tools.
11. A riveting machine in which are combined the following elements:—a supporting framework which comprises two separated upright standards, an angular bed plate having fastening devices thereon mounted upon one of said standards for retaining in horizontal fixed position a pneumatic tool, means mounted upon the other of said standards for retaining in adjustable position and in horizontal alinement with the first tool, an adjustable pneumatic tool, and a motive fluid supply under the control of the operator for simultaneously operating both tools.
12. A riveting machine in which are combined the following elements:—a supporting framework which comprises two separated upright standards, means mounted upon one of said standards for retaining in fixed horizontal position a pneumatic tool, means mounted upon the other of said standards for retaining in adjustable position and in horizontal alinement with the first tool, an adjustable pneumatic tool, a foot actuated motive fluid supply under the control of the operator for longitudinally positioning the adjustable tool, and a foot actuated motive fluid supply similarly under the control of the operator for simultaneously operating both tools, said foot actuated devices being located at the lower portion of one of said standards at opposite sides thereof.
13. A riveting machine in which are combined the following elements:—a supporting framework which comprises two separated upright standards, a casing mounted upon one of said standards for receiving and retaining in fixed horizontal position a pneumatic tool, a guiding casing mounted upon the other of said standards for receiving and retaining in adjusted position and in horizontal alinement with the first tool, the forward portion of an adjustable pneumatic tool, means likewise mounted upon said other of said standards for effecting the longitudinal horizontal positioning of said

adjustable tool, means under the control of the operator for controlling said adjusting means, and means similarly under the control of the operator for simultaneously operating both tools, said last two mentioned means being located at the lower portion of one of said standards at opposite sides thereof.

14. A riveting machine in which are combined the following elements:—a supporting framework which comprises two separated standards, a casing mounted upon one of said standards for receiving and retaining in horizontal fixed position a pneumatic tool, a guiding casing mounted upon the other of said standards for receiving and retaining in adjustable position and in horizontal alinement with the first tool, an adjustable pneumatic tool, means mounted upon said other of said standards for effecting the longitudinal adjustment of said adjustable tool, a seat for the operator below said adjustable tool, a motive fluid supply under the control of the operator for controlling said adjusting means, and a motive fluid supply similarly under the control of the operator for simultaneously operating both tools.

15. A riveting machine in which are combined the following elements:—a supporting framework which comprises two separated upright standards, a horizontal pneumatic tool fixed upon one of said standards, a pneumatic tool upon the other of said standards horizontally alined with the first tool, a seat for the operator below said last mentioned tool, and foot-controlled means below said seat and under the control of the operator for simultaneously operating both tools.

16. A riveting machine in which are combined the following elements:—a supporting framework which comprises two separated standards, a bed plate on one of said standards, a horizontal pneumatic tool fixed on said bed plate, a horizontal pneumatic tool adjustable upon the other of said standards toward and from said first tool and horizontally alined therewith, a seat for the operator below said adjustable tool, foot-controlled means below said seat under the control of the operator for longitudinally positioning said adjustable tool, and foot-controlled means also below said seat and similarly under the control of the operator for simultaneously operating both tools.

17. A riveting machine in which are combined the following elements:—a supporting framework which comprises two separated standards, a horizontal pneumatic tool fixed upon one of said standards, a horizontal pneumatic tool upon the other of said standards horizontally alined with the first tool, a seat for the operator and a foot-controlled

means below said seat for governing a motive fluid supply under the control of the operator for simultaneously operating both tools.

18. A riveting machine in which are combined the following elements:—a supporting framework which comprises two separated standards, a horizontal pneumatic tool fixed upon one of said standards, a horizontal pneumatic tool adjustable upon the other of said standards toward and from said first tool and horizontally alined therewith, a seat for the operator supported from one of said standards, a foot-controlled means also supported on one of said standards for governing a motive fluid supply under the control of the operator for longitudinally positioning the adjustable tool, and a foot-controlled means supported on the opposite side of said latter standard for governing a motive fluid supply similarly under the control of the operator for simultaneously operating both tools.

19. A riveting machine in which are combined the following elements:—a supporting framework which comprises two separated standards, a casing mounted upon one of said standards for receiving and retaining in horizontal fixed position a pneumatic tool, a casing mounted upon the other of said standards for receiving and retaining in adjusted position and in operative alinement with the first tool, an adjustable pneumatic tool, fluid-controlled means likewise mounted upon said other of said standards for effecting the longitudinal adjustment of said adjustable tool, a foot-controlled means under the control of the operator for governing a motive fluid supply for longitudinally adjusting said fluid-controlled means, and a foot-controlled means under the control of the operator for governing a motive fluid supply for simultaneously operating both tools, said pair of foot controlled means being located at the lower portion of one of said standards and on opposite sides thereof.

20. A riveting machine in which are combined the following elements:—a supporting framework which comprises two separated standards, a casing mounted upon one of said standards for receiving and retaining in fixed position a pneumatic tool, a pneumatic tool, a casing mounted upon the other of said standards for receiving and retaining in adjusted position and in operative alinement with the first tool, an adjustable pneumatic tool, a pneumatic cylinder likewise mounted upon said other of said standards, the piston of which is connected with said adjustable pneumatic tool for effecting the longitudinal adjustment of said adjustable tool, a foot-controlled valve by means of which the operator governs a motive fluid supply to said cylinder to regulate the movement of

- its piston, a second foot-controlled valve by means of which the operator governs a motive fluid supply to occasion the simultaneous operation of both pneumatic tools, 5 said foot controlled valve being located on opposite sides of said standards, pipe connections between the valve which governs the motive fluid supply to the cylinder, and pipe connections between the valve which 10 governs the motive fluid supply to both pneumatic tools.
21. A riveting machine in which are combined the following elements:—a supporting framework which comprises two separated 15 standards, a tool casing mounted upon one of said standards and provided with an upturned abutment, a pneumatic tool adapted to be received within and retained by said casing so that its handle is held fixedly 20 against said abutment, another tool casing mounted upon the other of said standards, an adjustable pneumatic tool formed without a handle and adapted to be received by and within said other casing, a pneumatic 25 cylinder mounted upon said second standard in axial alinement with and to the rear of the casing for the adjustable tool, a piston for said cylinder, having a protruding end provided with a tool head adapted to be connected 30 with the handle end of said adjustable pneumatic tool, a foot-controlled means for governing a motive fluid supply for controlling the piston and adjustable tool, and a foot-controlled means for governing a motive 35 fluid supply to both pneumatic tools.
22. In a double riveter, a plurality of upright standards, an angular plate having an upward extension mounted on one of said standards, a horizontal pneumatic riveter 40 fixedly secured to said plate and having its rear portion abutting against said upward extension, an adjustable horizontal pneumatic riveter mounted on the top of said other standard, and a guide on said latter standard for the forward portion of said adjustable riveter.
23. In a double riveter, a plurality of upright standards, an angular plate having an upward extension mounted on one of said standards, a horizontal pneumatic riveter 45 fixedly secured to said plate and having its rear portion abutting against said upward extension, an adjustable horizontal pneumatic riveter mounted on the top of said other standard, and a guide on said latter
- standard for the forward portion of said adjustable riveter, in combination with a seat for the operator supported on the standard carrying said adjustable riveter and foot actuated mechanism below said seat also 50 supported from said seat standard for actuating said riveters.
24. In a double riveter, a plurality of upright standards, an angular plate having an upward extension mounted on one of said standards, a horizontal pneumatic riveter fixedly secured to said plate and having its rear portion abutting against said upward extension, an adjustable horizontal pneumatic riveter mounted on the top of said other standard, and a guide on said latter standard for the forward portion of said adjustable riveter, in combination with an operator's seat supported on the standard carrying said adjustable riveter, lateral 55 plates secured to opposite sides of the lower portion of said seat carrying standard, foot 60 pedals on opposite sides of said standard and supported in said plates and fluid pressure means controlled by said pedals for advancing said adjustable riveter toward said fixed riveter and for their simultaneously actuating both of said riveters.
25. In a double riveter, means for supporting a horizontal riveter in fixed position, means for supporting a horizontal riveter in alinement therewith in adjustable position, foot controlled means for actuating said adjustable riveter toward or away from said fixed riveter, and a second foot controlled 65 means for simultaneously admitting motive fluid to both riveters for actuating them in unison.
26. In a double riveter, a stationary riveter, means for supporting it in fixed position, an adjustable riveter in alinement with said stationary riveter, means for supporting said adjustable riveter and for guiding it in its movements, a fluid supply to said riveter, controlling means for said fluid supply for actuating said adjustable riveter toward or away from said fixed riveter and a separate controlling means for simultaneously admitting motive fluid to both riveters for actuating them in unison.

WILLIAM LINDSAY SIMPSON.
